UNITED STATES PATENT OFFICE.

WILLIAM S. TOPPER AND JOSEPH A. ADAMS, OF BUCYRUS, OHIO.

SELF-LOCKING SWITCH.

Application filed January 27, 1922. Serial No. 532,196.

To all whom it may concern:

Be it known that we, WILLIAM S. TOPPER and JOSEPH A. ADAMS, citizens of the United States of America, residing at Bucyrus, in the county of Crawford and State of Ohio, have invented new and useful Improvements in Self-Locking Switches, of which the following is a specification.

The object of the invention is to provide simple and efficient means for locking a railway switch in its adjusted positions without especial action on the part of the switchman and under conditions necessitating special action in order to change the adjustment, to the end that accidents due to neglect on the part of the switchman to lock the switch in its adjusted position may be avoided; and with this object in view the invention consists in a construction and combination of parts of which a preferred embodiment is shown in the accompanying drawings, wherein:

Figure 1 is an elevation partly in section of a switch stand constructed with seal locking means embodying the invention.

Figure 2 is an end view of the same.

The device embodies a base 10 upon which is pivotally mounted the switch lever 11 by the operation of which the switch tongue (not shown) may be moved from the closed to the open position, or the reverse, said arm in the drawing being shown respectively in full and dotted lines in the opposite set positions, in one of which the switch is closed and in the other of which the switch is open, and also in dotted lines in an intermediate or transitory position from which it is adapted to drop in one direction or the other to an adjusted position. The switch arm is provided at an intermediate portion of its length with a head 12 extending in opposite directions from the side lines of the lever and provided in each of its projecting portions with a notch or seat 13 for engagement by a latch 14, one of which is mounted at each end of the base 10 in a guide 15 formed therein and which is beveled at its upper side as indicated at 16 so that when the switch lever drops in either direction from the neutral position it represses the corresponding latch against the tension of an actuating spring 17 and is locked by the engagement of the latch with the corresponding seat or notch 13, to the end that in order to again shift the position of the

switch it is necessary to unlock the switch lever by retracting the engaged latch.

Each latch is provided with a stem 18 upon which the spring 17 is coiled and which spring bears at its outer end against a shoulder 19 formed by the inner end of the latch head proper and a shoulder 20 formed by a reduction in the guide 15, said stem terminating at its inner end in a button 22 arranged in the path of a key insertable transversely through a key slot 23 formed in the side of the base and communicating with an enlargement 24 of the guides in which the latches are mounted.

It will be seen that the head with which the switch lever is provided serves not only as one element of the locking means by which the lever is secured in either of its adjusted positions, but acts as a weight to insure the positive movement of the lever to the limit of its path of operation, so that the locking thereof is assured, and in addition thereto constitutes a means of concealing and protecting the latch which is engaged therewith against surreptitious repression or disengagement.

Moreover the buttons at the inner ends of the latch stems are arranged so close together that if one of the latches is repressed to a position such that it will not engage and lock the switch lever when in one position (assuming that it might be repressed and secured by extraneous means for the purpose of preventing the locking of the switch lever thereby) the other latch could not be withdrawn sufficiently to release the switch arm with which it is engaged, and it would thereupon immediately become apparent that the switch stand had been tampered with or that it was not in a condition to properly perform its functions. In other words the interval between the button at the inner ends of the latch stems is preferably only equal to the necessary throw of one latch in order to disengage that latch from the seat in the switch lever head with which it is engaged, and that when one latch is retracted to release the switch lever the other latch must be in its extended or engaging position.

Having described the invention, what is claimed as new and useful is:—

1. A switch stand having a base, a switch lever pivotally mounted on the base for swinging movement to opposite positions in

substantial parallelism with the base, and locking means having spring actuated latches mounted for projection at opposite ends of the base for engagement with the switch lever at the limits of its swinging movement, the switch lever having a head extending in opposite directions laterally from the lever to form projections adapted to overlap the end edges of the base and provided in said overlapping portions with seats or notches for the respective reception of the latches.

2. A switch stand having a base, a switch lever pivotally mounted on the base for swinging movement to opposite positions in substantial parallelism with the base, and locking means having spring actuated latches mounted for projection at opposite ends of the base for engagement with the switch lever at the limits of its swinging movement, said latches having stems provided at their inner ends with spaced but-

tons accessible through a keyhole slot formed in the side of the base.

3. A switch stand having a base, a switch lever pivotally mounted on the base for swinging movement to opposite positions in substantial parallelism with the base, and locking means having spring actuated latches mounted for projection at opposite ends of the base for engagement with the switch lever at the limits of its swinging movement, said latches having stems provided at their inner ends with spaced buttons accessible through a keyhole slot formed in the side of the base, the interval between said buttons being substantially equal to the movement of a latch necessary to effect disengagement thereof from the switch lever with which it is engaged.

In testimony whereof they affix their signatures:

WILLIAM S. TOPPER.
JOSEPH A. ADAMS.
